Alfred W. Madl, Milwaukee, Wis., assignor to John Oster
Manufacturing Co., Milwaukee, Wis., a corporation of
Wisconsin

Filed Apr. 11, 1961, Ser. No. 64,695

Term of patent 14 years

(Cl. D22—5)

Fig. 1.

Fig. 2.

Fig. 3.

Fig. 4.

FIGURE 1 is a top perspective view of an electric hair clipper embodying my new design;

FIGURE 2 is a bottom perspective view thereof;

FIGURE 3 is a side elevational view thereof; and

FIGURE 4 is a top plan view thereof.

The dominant features of my design reside in those portions thereof shown in solid lines and consist primarily in the front end portion of the clipper body, and particularly the long sweeping inward curve of its sides from their junction with the surface of the cylindrical handle portion of the body as viewed from the top (FIG. 4) and the complementarily convexly bowed side edges of the cover plate all as shown.

I claim:

The ornamental design for an electric hair clipper, as shown and described.
